Des. 227,648
Patented July 10, 1973

227,648

HOUSING FOR A RUG SHAMPOOER

Robert A. Yonkers, Grandville, Mich., assignor to Bissell Inc., Grand Rapids, Mich.

Filed June 9, 1971, Ser. No. 151,629

Term of patent 14 years

Int. Cl. D7—05

U.S. Cl. D7—170

Fig. 1

Fig. 2

Fig. 3

Fig. 4

FIG. 1 is a front elevational view of a housing for a rug shampooer showing my new design;

FIG. 2 is a rear elevational view thereof;

FIG. 3 is a side elevational view thereof, the side opposite being a mirror image; and

FIG. 4 is a top plan view thereof.

I claim:

The ornamental design for a housing for a rug shampooer, substantially as shown and described.
